UNITED STATES PATENT OFFICE.

JOSEPH A. YOUNT, OF LACLEDE, MISSOURI.

DESIGN FOR A MEDAL.

SPECIFICATION forming part of Design No. 22,241, dated February 28, 1893.

Application filed November 26, 1892. Serial No. 453,279. Term of patent 3½ years.

To all whom it may concern:

Be it known that I, JOSEPH A. YOUNT, of Laclede, in the county of Linn and State of Missouri, have invented and produced a new and original Design for a Medal, of which the following is a specification.

Reference is to be had to the accompanying drawings forming a part of this specification, in which similar letters of reference indicate corresponding parts in both the figures.

Figure 1 represents the obverse; and Fig. 2 the reverse of a medal embodying my new design.

The design consists in the configuration and

ornamentation shown. Thus the medal is in the form of a thirteen sided figure, the divisions thus corresponding to the number of original States of the United States. On the front of the medal appears the head of Columbus. On the reverse of the medal appears the representation of an exposition building.

I claim—

The design for a medal herein shown and described.

JOSEPH A. YOUNT.
